UNITED STATES PATENT OFFICE.

WILLIAM N. WHITELY, OF SPRINGFIELD, OHIO.

BICYCLE.

SPECIFICATION forming part of Letters Patent No. 707,480, dated August 19, 1902.

Application filed January 13, 1897. Serial No. 619,035. (No model.)

To all whom it may concern:

Be it known that I, WILLIAM N. WHITELY, a citizen of the United States, residing at Springfield, in the county of Clark and State 5 of Ohio, have invented certain new and useful Improvements in Bicycles, of which the following is a specification.

My invention relates to improvements in bearings for bicycles and other vehicles; and 10 the object of my invention is to improve the details of construction so as to create a more perfect bearing and at the same time simplify the parts and process of construction. I attain these objects by the constructions shown 15 in the accompanying drawings, in which—

Figures 1 and 2 are respectively a longitudinal section and side elevation of the main axle-bearing. Fig. 3 is a longitudinal section of the driving-wheel hub and bearing, 20 and Fig. 4 is a detail of same.

Like parts are represented by similar letters of reference in the several views.

In this bearing I employ an axle e and an outer hub or barrel e' , one of which parts revolves while the other is stationary. When 25 employed for the crank-hanger, the barrel is stationary and the axle revolves. When employed in the wheel, the axle is stationary while the barrel revolves. Both ends of this 30 barrel or hub are preferably internally screw-threaded and both ends provided with extended portions which project beyond the screw-threaded portions. In one end this extended portion is formed tapered on the inside, 35 as shown at e^2 . The other end has a straight portion, as shown at e^3 . In each end there is secured a ball-cup e^4 and e^5 . Each of these ball-cups is provided with a screw-threaded portion and an extended portion. On the 40 ball-cup e^4 the extended portion is formed on a taper to fit the taper e^2 , formed on the barrel of the hub. The ball-cup e^5 is formed with a straight periphery adapted to fit snugly in the bore e^3 of the barrel or hub. In assembling 45 the parts the ball-cup e^4 is screwed tightly into position, the screw-threads drawing the tapered portion into said barrel so as to exactly center the same and at the same time secure it tightly against displacement. 50 The ball-cup e^5 is adapted to be adjusted longitudinally in the hub or barrel, and while the screw-threads perform this adjustment

the extended portion fitting snugly into the extended bore of the hub holds the parts in perfect alinement while the adjustment is 55 being accomplished.

To provide for holding the adjustable cup e^5 in the proper relative position of adjustment, I preferably provide the outer periphery of the extended portion with notches e^6 , 60 and in the hub or barrel there is provided a set-screw e^7 , which has an extended portion e^8 to fit in said notches. It will be understood that the outer periphery of this extended portion or the ribs or ridges between the 65 notches are fitted accurately to the bore, so that while the bearing may be moved out and in by the screw-threads it is held in positive alinement by these portions, while the threads serve the purpose only of moving 70 the same in or out. By tightening the screw e^7 into one of the notches or recesses the bearings may be held in the proper adjusted position. It is obvious that the same or substantially the same result may be had 75 without the notches, the set-screw or other securing device being adapted to impinge against the outer smooth periphery of the extended portion of the ball-cup. The axle e is provided with cone-shaped lugs or shoulders e^9 , which are opposed to the ball-cups e^4 e^5 , and antifriction-balls e^{10} are placed between said cones and cups in the usual way. When it is desirable to mount these cones or 80 shoulders on the axle in separate pieces in 85 the nature of sleeves which may be hardened, I preferably form the interior of the sleeve with a series of serrations and form said axle slightly larger than the serrated interior of the sleeve. The sleeve is then forced onto 90 the axle and being of harder metal than the axle the serrations seat themselves therein, forming corresponding grooves, as shown at the left in Fig. 4, and thus secure the parts firmly together without further means of fastening. The ends of the ball-cups e^4 e^5 are 95 preferably provided with extended engaging parts e^{11} , of polygonal shape, to which a wrench or other device may be applied in turning the same to their proper positions of 100 adjustment.

Having thus described my invention, I claim—

1. A barrel or hub of a vehicle-bearing, hav-

ing a straight internal screw-threaded portion, and an enlarged plain tapered portion at the end, in combination with a ball-cup screwed into said screw-threaded portion, having an enlarged plain tapered end fitting the taper of said barrel or hub, for the purpose of securely connecting said ball-cup to said barrel or hub, substantially as specified.

2. In a vehicle-bearing, a barrel or hub, a shouldered axle extending through the same, ball-cups arranged adjacent to said shoulders, and balls between said cups and shoulders, each of said ball-cups being screw-threaded on a portion of the periphery and a plain extension on the remainder of the periphery, one of

said ball-cups having its plain extension tapered and the other ball-cup having its extension grooved, the barrel being formed at each end to conform to said extended portions, and means on each of said cups for turning the same into said barrels, and a set-screw adapted to engage the grooves on one of said cups, substantially as specified.

In testimony whereof I have hereunto set my hand this 6th day of January, A. D. 1897. 25

WILLIAM N. WHITELY.
